GAS GENERATOR

Gustav Steiner, Ludwigshafen - on - the - Rhine,
Germany, assignor to Wilhelm Dützmann,
Neustadt-on-the-Haardt, Germany

Application July 3, 1936, Serial No. 88,911
In Germany July 4, 1935

5 Claims. (Cl. 48—144)

This invention relates to a method and device for converting liquid, particularly difficultly volatile, fuels into a gaseous state so as to render them suitable for operating internal combustion engines.

The method according to the invention consists in gradually adding water vapor with air and fresh air to the difficultly volatile fuels previously subjected to atomization and the impact 10 with heated walls and in compensating at least after each addition the drop in temperature caused thereby by a supplementary supply of heat. This gradual mixing of the fuel constituents with air insures a remarkably uniform 15 and economical distribution of the particles of fuel in the mixture. The application of the method requires of course considerable heat which, according to the invention, is supplied by passing additional oxygen or air to the exhaust 20 gases flowing around the spaces wherein the mixture is homogenized and thus causing the unburned constituents still contained in the exhaust gases to be burnt.

The device for carrying out this method comprises a plurality of spaces wherein the difficultly volatile and atomized fuel coming from a nozzle 25 is heated, split up and mixed with water vapor, and a coil to which additional air is supplied at one or more places. The spaces mentioned are 30 surrounded by the exhaust gases and heated. At the end of the coil a mixing device is provided, in which the homogenized gas mixture developing in the coil is supplied with air to the required extent. The exhaust piping contains nozzles or 35 other means through which air can flow in.

By way of example, the invention is illustrated in the accompanying drawing, in which Figure 1 is a section of the device attached to an engine and Fig. 2 a detail view on an enlarged scale of the mixing nozzle.

Referring to the drawing, 2 is the exhaust piping of the engine, which contains in a relatively enlarged extension 2' the parts required for producing the fuel mixture, i. e., a superheating space 10, a mixing space 12 and a connecting coil 3 surrounded on all sides by the hot exhaust gases. The difficultly volatile fuel to be converted is supplied through the nozzle 6. The mixing space 12 is in communication with a device 5 for enriching the moisture content of the primary air in such manner that the air drawn in through the openings 17 is forced to pass along the moist wick 14. At the lower end of the coil 3 a second coil 18, also surrounded by exhaust gases, is provided for supplying fresh air when

operative and also serving for discharging oil which has accumulated as liquid in the coil when the device is idle. In the mixing device 7 the homogenized fuel mixture is mixed with the final amount of air and thence passes into the suction connection of the engine.

The device functions as follows:

For starting the engine is actuated by means of the gasoline carburetor 24. When the engine has been idling for about five minutes or the 10 vehicle has run 1 km., the gasoline supply can be stopped and the engine operated with difficultly volatile fuel. If the crude oil valve is actuated by the usual foot levers, the crude oil first enters the superheating jacket or hot bulb 10 15 through a calibrated nozzle and then through the guide pipe 11 the mixing member 12 into which the air channel 13 opens. The channel 13 is in communication with a device 5 comprising a lower part filled with water or another suitable 20 liquid into which the wick 14 extends which leads to the upper part of the device 5. The upper part is perforated like a sieve and provided with a connection 15.

When the oil valve is actuated the flap 16 opens 25 and the suction effect of the engine continues through the coil 3, so that air is drawn in through the bores 17 shown in Fig. 1, enriched with water vapor and drawn into the mixing space 12. In the meantime, the crude oil has been physically 30 disintegrated by passing the hot bulb 10 and enters into reaction with the water particles contained in the air current, whereby the formation of a permanent gas is initiated. The heat lost by the addition of the mixture of air and water 35 vapor is supplied again to the developing gas while it flows through the inner coil. After the inner coil has been passed a small amount of air in superheated form is supplied for rapid conversion which is effected in the outer coil. The 40 coil 18 acts as air heater and also prevents the coil 3, during stopping of the engine, from filling with oil, possibly owing to a leak in the oil valve, which would have disastrous consequences when the engine is started.

The gas formed then passes to the mixing member 7 provided on its front side with the air admission bores 19 normally shut off by the spring plate 20 in the absence of engine suction.

The inside further contains the air funnel 21 50 adjustable from without and the cone 22 which regulates the gas supply and can also be adjusted from the outside. The cone 22 as well as the air funnel 21 are connected through the wall of the mixing device 7 by bolts movable in slots in 55

the wall to permit adjustment, and fixed in adjusted position by thumb nuts.

This device serves for insuring some movement of the gas and more intensive whirling with the air that follows. Heating of the spaces wherein the fuel mixture is homogenized is effected by supplying the exhaust gases coming out of the cylinder 1 with oxygen, for instance in the form of atmospheric air, and burning it together with the unburned constituents of the exhaust gases. This is brought about by means of a nozzle 23 inserted between the exhaust flange and the cylinder block and made of heat- and corrosion-resisting material and by providing the exhaust pipe 2 on its circumference with holes 25 which permit the supply of at least 20% air to the exhaust flame.

Owing to the suction effect produced by the rapidly emerging waste gases, the flame is automatically enriched with air, regenerated and simultaneously consumes all carbon monoxide and fuel residues still contained in the waste gases, so that smokeless exhaust is insured even in case of lined pistons and valves.

The increase in temperature attained by this device, with a certain excess as safety factor, fully suffices for operating the engine with difficultly volatile fuel even when idling.

I claim:

1. A gas generator for converting difficultly volatile fuels into a mixture suitable for operating combustion engines, comprising a volatilizing

chamber, means for admitting the fuel to the chamber for volatilizing, a mixing chamber, means for admitting the volatilized fuel to the mixing chamber, an air moistening device, means for admitting moistened air from the air moistening chamber to the mixing chamber for mixing with the volatilized fuel, means for directing the mixture through a tortuous path under the suction of the engine, means for admitting supplementary air to the mixture at a predetermined point in this path, and means for subjecting the volatilizing chamber, mixing chamber and tortuous path of the mixture to the continuous action of heat.

2. A construction as defined in claim 1, where- 15 in the means for admitting additional air to the tortuous path of the mixture is located to serve as a relief from such tortuous path of any condensate accumulating when the generator is idle.

3. A construction as defined in claim 1, where- 20 in means are provided open to the passage of the mixture under the suction of the engine for admitting to such mixture an additional air supply in accordance with the demands of the engine.

4. A construction as defined in claim 1, where- 25 in the tortuous path is in the form of a coil having an inner depending section and an outer rising section.

5. A construction as defined in claim 1, where- 30 in the means for heating is supplied by the exhaust from the engine.

GUSTAV STEINER.
